UNITED STATES PATENT OFFICE.

JOHN C. SHAMBOW, OF WOONSOCKET, RHODE ISLAND, ASSIGNOR TO SHAMBOW SHUTTLE COMPANY, OF WOONSOCKET, RHODE ISLAND, A CORPORATION OF RHODE ISLAND.

DROP-BOX LOOM.

Application filed October 7, 1924. Serial No. 742,172.

To all whom it may concern:

Be it known that I, JOHN C. SHAMBOW, a citizen of the United States, residing at Woonsocket, in the county of Providence and State of Rhode Island, have invented certain new and useful Improvements in Drop-Box Looms; and I do hereby declare the following to be a full, clear, and exact description of the invention, such as will 10 enable others skilled in the art to which it appertains to make and use the same.

The present invention relates to an improvement in drop box looms.

Plain drop box looms were provided with 15 shuttles which had the delivery eye in the end of the shuttle nearer the selvage when the shuttle was boxed on the drop box side of the loom. In this loom the butt of the bobbin was located at the opposite end of 20 the shuttle from the shuttle eye. These looms were satisfactory in operation, but with the advent of the use of feelers the weavers attempted to apply the feeler to the loom. Inasmuch, however, as the feelers 25 were mounted on the single box side of the loom and usually made their feeling movement in a direction outward from the side of the loom upon which they were mounted, such a feeler was not adapted for use with 30 the shuttles employed in the loom. Consequently opposite hand shuttles were employed in the looms in order to adapt them to the use of the feeler mechanism. This, however, although it brought the butt of 35 the bobbin in the right position for the feeler, resulted in the maloperation of the drop box, because it threw the eye of the shuttle into the shuttle box on the drop box side of the loom at the end of the shuttle 40 remote from the selvage with the result that the yarn frequently was caught between the binder and the shuttle due to the lifting and falling of the drop box. The present invention 45 contemplates the use in a drop box loom of the filling feeler type of a shuttle having its eye at the same end as the butt of the bobbin and located in a plane non-registering with the feeler hole of the shuttle.

The present invention consists in the box 50 loom hereinafter described and particularly defined in the claims.

In the accompanying drawings Fig. 1 is a diagrammatic view of a plain box loom embodying the invention; Fig. 2 is a plan,

and Fig. 3 an elevation of a shuttle for the 55 looms.

The illustrated embodiment of the invention is described as follows:—The cloth being woven is indicated at 10, the selvages of the cloth are indicated at 11, and the single 60 box 12 is shown at the one side and the drop box 13 at the other side of the loom. The loom is provided with a filling feeler 14, stopping mechanism 15, and connections therebetween 16. A filling fork 17 is provided, also connected with the stopping mechanism by the connections 18. The shuttle 20 employed in the loom is provided with a feeler hole 21 through which the feeler enters the shuttle and feels of the yarn 70 on the bobbin. When the yarn is exhausted to a predetermined extent, determined by the operation of the feeler, it stops the loom and the operative places a new bobbin in the shuttle. The shuttle is provided with a 75 delivery eye 27 which is located in fixed position at the bobbin butt end of the shuttle, which is the end of the shuttle nearer the selvage when the shuttle is boxed on the drop box side of the loom. The yarn from 80 the bobbin extends from the tip of the bobbin through the guide eye 22 into the tension cavity in the end of the shuttle where it may be passed through a tension device, if desired, but which is shown as extending 85 directly from the guide eye 22 to the guide eye 23, which leads it from the tension cavity in the end of the shuttle to the top of the shuttle, or to a point near the top of the shuttle, where the yarn turns and enters 90 the yarn tube 24 through which the yarn extends to the opposite end of the shuttle. Here the yarn descends through the guide eye 25, which may be a delivery eye in case the thread is delivered at this point into the groove 26 in the upper part of the front side of the shuttle, or the eye 25 may be 95 merely a guide eye, in which case the yarn extends down to the delivery eye 27 near the bottom of the shuttle, where it delivers 100 the yarn to the groove 28 at the lower front corner of the shuttle.

The position of the delivery eye is important, and is made non-registering with the position of the feeler hole in the shuttle, so that when the shuttle is boxed on the filling feeler side of the loom there is no 105 possibility of the yarn being broken by the

blow of the feeler against it as the feeler enters the shuttle. The filling fork 17 on failure of the weft indicates absence and operates the stopping mechanism to stop the loom.

The shuttle herein described and claimed is particularly adapted for use in existing box looms provided with filling feelers because the location of the delivery eye of the shuttle on the side nearer the selvage when it is boxed on the drop box side of the loom reduces weft breakage, and the location of such eye in a plane non-registering with that of the feeler hole reduces a further liability of breakage by the feeler. Obviously the shuttle is of advantage even in looms unprovided with a feeler because of the reduction of weft breakage due to the action of the binders on the drop box side of the loom.

Having thus described the invention, what is claimed is:

1. A box loom of the filling feeler type having, in combination, a lay having a single box on one end and a drop box on the other end, a feeler on the single box side of the loom, a stop motion, connections between the stop motion and the feeler, shuttles for the boxes, each provided with a feeler hole and a yarn delivery eye located in the end of the shuttle nearer to the selvage when boxed on the drop box side of the loom.

2. A box loom of the filling feeler type having, in combination, a lay having a single box on one end and a drop box on the other end, a feeler on the single box side of the loom, a stop motion, connections between the stop motion and the feeler, shuttles for

the boxes, each provided with a feeler hole and a yarn delivery eye in the end of the shuttle nearer the selvage when the shuttle is boxed in the drop box side of the loom, said feeler hole and delivery eye being located in non-registering planes.

3. A shuttle for feeler looms having a body provided with a bobbin cavity, a feeler hole in the front of the shuttle, a delivery eye located at the bobbin-butt end of the shuttle, and yarn guiding means for leading the yarn from the bobbin to the delivery eye, said feeler hole and delivery eye being located in non-registering planes.

4. A shuttle for feeler looms having a body provided with a bobbin cavity, a feeler hole in the front of the shuttle, a delivery eye located at the bobbin-butt end of the shuttle and yarn guiding means for leading the yarn from the bobbin to the eye.

5. A shuttle for feeler looms having a body provided with a bobbin cavity, a feeler hole in the front of the shuttle, a delivery eye located at the bobbin-butt end of the shuttle and yarn guiding means for leading the yarn from the bobbin to the eye, comprising a yarn tube extending alongside of the bobbin cavity to protect the yarn from contact with the yarn running off the bobbin.

6. A shuttle for box looms having a body provided with a bobbin cavity, a delivery eye fixed at the bobbin butt end of the shuttle, and yarn guiding means for leading the yarn from the bobbin to the eye.

In testimony whereof I have signed my name to this specification.

JOHN C. SHAMBOW.
